UNITED STATES PATENT OFFICE.

IRA S. FISHER, OF KELLER, VIRGINIA, ASSIGNOR OF ONE-HALF TO WILLIAM W. MUNDY, OF MOLINO, MISSOURI.

RAILROAD TIE AND BALLAST.

1,141,049.

Specification of Letters Patent. Patented May 25, 1915.

Application filed January 12, 1915. Serial No. 1,845.

To all whom it may concern:

Be it known that I, IRA S. FISHER, a citizen of the United States, residing at Keller, in the county of Accomac and State of Virginia, have invented certain new and useful Improvements in Railroad Ties and Ballasts; and I do hereby declare the following to be a full, clear, and exact description of the invention, such as will enable others skilled in the art to which it appertains to make and use the same.

This invention relates to a railway road bed, and the primary object of the invention is to provide a road bed including ballasts and rail supporting ties, which are particularly adapted for providing a smooth and even railway for the travel thereover of ordinary railway rolling stock, and to eliminate rough travel due to the sinking or sagging of certain parts of the road bed and also to decrease the cost of upkeep of a road bed.

Another object of this invention is to provide a novel form of metallic rail tie and rail chair for engaging the bases of ordinary T-rails for rigidly holding them in place, which rail chair may be easily and quickly adjusted for removing a rail when desired, or for inserting or replacing a rail when necessary.

Another object of this invention is to provide a rail tie which is adjustable so that the length of the same may be varied as required for firm binding supporting engagement with the road bed or ballast.

A still further object of this invention is to provide a rail tie which is composed of a plurality of sections, and to insulate these sections from each other at the central portion of the road bed, so as to insure the efficient operation of electrical block sections or the like.

With the foregoing and other objects in view this invention consists in such novel features of construction, combination and arrangement of parts as will be hereinafter more fully described, illustrated in the accompanying drawings and claimed.

In describing the invention in detail reference will be had to the accompanying drawings wherein like characters designate like or corresponding parts throughout the several views, and in which:

Figure 1 is a top plan view of a part of a road bed constructed in accordance with

this invention. Fig. 2 is a vertical cross sectional view through the same. Fig. 3 is a plan view of a switch or side track construction. Fig. 4 is a detail perspective view of the rail chair employed in the construction of a road bed. Fig. 5 is a detail perspective view of a section of the rail tie. Fig. 6 is a cross sectional view on the line 6-6 of Fig. 2, and Fig. 7 is a detail perspective view of a plate used in the construction of the rail tie.

Referring more particularly to the drawings, 1 designates the road bed or ballast for the track as an entirety, which is formed of concrete abutments or supports 2 which are placed within the ground 3 and have mounted upon their upper surfaces tie supporting concrete abutments 4. The tie supporting concrete abutments 4 are spaced from each other, and a concrete bed 5 is mounted between them, having its marginal edges resting upon the upper surfaces of the inner corners of the abutments 2. The upper surface of the bed 5 is arcuate as is shown at 6, and is positioned beneath the upper surfaces 7 of the abutments 4 leaving a space 8 between the facing sides of the abutments 4 as is clearly shown in Fig. 2 of the drawings. The space 8 is provided for receiving the vertically depending sections of the rail tie 10 which is designated by the numeral 10 as an entirety. The tie 10 is composed of two sections 11 and 12, which sections are mounted upon the opposite side of the road bed and extend inwardly to the center thereof, having their meeting ends connected by fish plates 13, which are securely bolted to the sides of the depending plates 14 and 15 of the sections 11 and 12. The depending plates 14 and 15 have their upper marginal edges bent at right angles to the vertical portions thereof, forming horizontally disposed supporting arms 16, upon which rest the horizontal plates 17. The horizontal plates 17 terminate a short distance from the center of the road bed, and have their outer ends 18 which rest upon the upper surfaces of the abutments 4 enlarged and thickened as is clearly shown by reference to Figs. 2 and 4 of the drawings. The enlarged ends 18 of the plates 17 form supporting bases of the rail chairs 20. The rail chairs 20 comprise the bases 18 and a pair of rail base gripping members 21 and 22, which are secured to the upper surface of the bases 18, 110

by bolts indicated at 23, so that they may be removed therefrom if it is so desired. The blocks 21 and 22 have their facing sides cut away as is shown at 24 so as to receive the 5 marginal edges of the base 25 of an ordinary T-rail 26 used in railway road bed constructions. The block 22 is positioned at the outer end of the bases 18 while the block 21 is positioned upon the inner sides of the 10 T-rail and has its inner edge 27 cut obliquely to the line of extension of the T-rail 26.

The plates 17 have plates 30 and 31 mounted upon their upper surfaces, the plate 31 15 extending from the center of the road bed to and over the vertical section 15 of the tie structure, while the plate 30 extends over the vertical section 14 of the tie as is clearly shown in Fig. 2 of the drawings. The plates 20 30 and 31 have transversely extending projections 32 formed upon their corresponding side edges at their outer ends, which extensions or projections 32 have vertically extending plates 33 formed upon their outer 25 marginal edges. The vertical plates 33 extend upwardly and are spaced a short distance outwardly from the marginal edge of the plates 30 and 31 and are provided with openings 34 extending therethrough, through 30 which bolts 35 are inserted. The bolts 35 are inserted through openings 36 which extend longitudinally through the plates or blocks 21, and by tightening the nuts upon the ends of the bolts 35, the blocks 21 are 35 wedged against the angular end 36 of plates 37. The plates 37 are secured to the upper surfaces of the plates 30 and 31 by bolts 38 which have their heads countersunk into the plates so as to provide a perfectly smooth 40 surface thereover. The plates 30 and 31 are secured to the upper surface of the plates 17 by countersunk bolts 39 which are spaced along the edges of the plates as is clearly shown in Fig. 1 of the drawings.

45 The plates 37 are secured to the upper surface of the plates 30 and 31 and project over upon the upper surface of the enlarged ends 18 of the plates 17, having their angle ends 36 provided for abutting engagement with 50 the angled ends 27 of the blocks 21 for forming a wedge connection between the plates and the blocks for securely forcing the blocks 21 against the base of the T-rails 26 for securely holding the T-rails positioned upon 55 the upper surface of the tie structure.

The plate 31 has its inner end bent downwardly as is shown at 40 for providing a pocket for receiving the inner end of the plate 30, so that the upper surface of the 60 plates will lie flush with each other and provide a smooth surface upon the top of the tie. A plate of insulation 41 is mounted between the inner ends of the plates 30 and 31 so as to insulate one plate from the other, 65 for preventing the passage of an electrical

current between the T-rails carried upon the opposite sides of the road bed, when these rails are conductors for various purposes such as the employment of block signals and the like such as are used upon railways as mounted constructions. The fish plates 13 are also insulated from the plates 14 and 15 by means of plates 13^a of insulation. 70

The vertical depending sections 14 and 15 of the rail tie 11 have plates 45 secured to the sides thereof adjacent their outer ends. The plates 45 have transversely extending heads 46 formed upon their outer ends which abut the inner surface of the abutment 4 for securely holding the rail tie in place upon the abutment. The plates 45 are provided with longitudinally extending slots 47 and 48 formed therein, through which extend bolts 49. The plates 45 are provided with corrugated surfaces 50 formed about the slots 47, which are provided for receiving corrugated nuts 51, that are carried by the bolts 49 intermediate of the plates 45 and the nuts 51 for holding the bolts firmly in position against accidental movement, after they have been properly adjusted to their proper position. The plates 14 are provided with slots 53, which align with the slots 47 and 48, so as to provide for the longitudinal adjustment of the plates 45 upon the depending vertical plates 14 and 15, for regulating the distance between the outer faces of the heads 46 of the plates, and providing firm abutting engagement between 100 the outer surfaces of the heads 45 and the inner surfaces of the abutment 4. 95

In Fig. 3 of the drawings, a switch or side track connection or construction is illustrated, which provides modified forms of the ties, including the ties 60 which are constructed in accordance with the generic idea of the tie illustrated in Figs. 1 and 2 as heretofore described, but the length of the various plates of which are varied, to accommodate the distances between the rails 61 which are used in the construction of the main line and the side tracks. The connected ends of the plates used in the construction of ties illustrated in this figure, are not insulated from each other, and the rails approaching the side tracks are insulated from the rails thereof and also the rails of the main line along side of the side tracks and the current for the operation of the block system is carried by an auxiliary rail or wire which is positioned along side of the ordinary track, (not shown) so as to eliminate the intricate construction which will be necessary in forming the plates in accordance with Figs. 1 and 2 of the drawings. 110

The adjustment of the length of the rail ties is provided to accommodate irregularity of the abutment spaces or properly gaging the T-rails. 125

In Fig. 1 of the drawings plates 70 are shown secured to the base of the rails 26, and held in firm engagement therewith by set screws 71. These plates 70 abut the upper 5 surface of the concrete abutments 4 and form midway bearings or supports for the rails for bracing them intermediate of the ties.

The concrete abutments 4 are provided 10 with openings 75 formed therein, which communicate with the space formed beneath the ties, and extend outwardly and downwardly therefrom so as to provide drainage openings for draining water from the 15 openings beneath the ties.

From the foregoing description taken in connection with the accompanying drawings the advantages of construction and of the method of operation of the improved railroad tie will be readily apparent to those skilled in the art to which this invention pertains, and while in the foregoing description, the principle of the operation of this invention has been described together with 20 various features of construction, it is to be understood that certain minor features of construction, combination and arrangement of parts may be altered to suit practical conditions provided such alterations are 25 comprehend within the scope of what is claimed.

What is claimed is:—

1. In a railway road bed construction, a pair of concrete abutments disposed in 35 spaced relation to each other, a plurality of rail ties carried by said abutments and having depending vertically disposed plates formed thereon, adjustable plates carried by said vertical plates and adjustable for abutment 40 with the facing sides of said concrete abutments for rigidly holding said ties in place.

2. In a railroad bed construction, a pair of concrete abutments disposed in spaced 45 relation to each other, a plurality of rail ties carried by said abutments and having depending vertically disposed plates formed thereon, adjustable plates carried by said vertical plates and adjustable for abutment 50 with the facing sides of said concrete abutments for rigidly holding said ties in place, and removable rail chairs carried by the upper surface of said ties.

3. In a railway road bed construction, rail 55 ties including a plurality of vertical plates, transversely extending supporting plates formed integrally with the upper edges of said vertical plates, horizontally positioned plates carried by said transversely extending 60 supporting plates, rail chairs connected to said horizontal plates, and plates adjustably connected to the sides of said vertical plates for varying the length of said ties.

4. In a railway road bed construction, rail 65 ties including a plurality of vertical plates,

transversely extending supporting plates formed integrally with the upper ends of said vertical plates, horizontally positioned plates carried by said transversely extending supporting plates, rail chairs connected to 70 said horizontal plates, and plates adjustably connected to the sides of said vertical plates for varying the length of said ties, plates detachably mounted upon the upper surface of said supporting plates, said plates extending into the center of said ties and being insulated from each other.

5. In a railroad bed construction, rail ties including a pair of vertical plates having their inner ends disposed in meeting engagement with each other, horizontally disposed plates carried by the upper edges of said vertical plates, blocks detachably carried by the outer terminal ends of said horizontal plates and forming rail chairs for engagement with the bases of ordinary T-rails, means for wedging said blocks into engagement with the rail base, and means for varying the length of said tie.

6. In a railroad bed construction, the combination with concrete abutments having their facing sides disposed in spaced relation to each other, of rail ties including a pair of vertically disposed plates having their meeting ends engaging each other equi-distant of the facing sides of said concrete abutments, plates slidably carried by said vertical plates, transversely extending heads formed upon the outer ends of said slidable plates for engagement with the facing sides of said concrete abutments, and means for rigidly holding said slidable plates in adjusted positions for regulating the length of the tie.

7. In a railroad bed construction, the combination with concrete abutments having their facing sides disposed in spaced relation to each other, of rail ties including a pair of vertically disposed plates having their meeting ends engaging each other equi-distant of the facing sides of said concrete abutments, plates slidably carried by said vertical plates, transversely extending heads formed upon the outer ends of said slidable plates for engagement with the facing sides of said concrete abutments, means for rigidly holding said slidable plates in adjusted positions for regulating the length of the tie, horizontal plates detachably carried by said vertical plates, rail chairs detachably connected to the ends of said horizontal plates, and means for wedging the rail chairs into firm binding engagement with the bases of T-rails.

8. In a railroad bed construction, a pair of concrete abutments disposed in spaced relation to each other, a concrete bed extending from one of said abutments to the other below the upper surfaces thereof, a plurality of rail ties carried by said abutments and

having depending vertically disposed plates formed thereon, adjustable plates carried by said vertical plates and adjustable for abutment with the facing ends of said concrete abutments for rigidly holding said ties in place, and removable rail chairs carried by the upper surface of said ties.

9. In a railway road bed construction, rail ties including a plurality of vertical plates, 10 transversely extending supporting plates formed integrally with the upper edges of said vertical plates, horizontally positioned plates carried by said transversely extending supporting plates, rail chairs connected 15 to said horizontal plates, plates adjustably connected to the sides of said vertical plates for varying the length of said ties, and means for wedging the rail chairs into firm engagement with the bases of T-rails.
10. In a railroad bed construction, the combination with concrete abutments having their facing sides disposed in spaced relation to each other, of a concrete bed extending from one of said abutments to the other 25 and positioned below the upper surfaces thereof, rail ties including a pair of vertically disposed plates having their meeting

ends engaging each other equi-distant of the facing sides of said concrete abutments, plates slidably carried by said vertical 30 plates, transversely extending heads formed upon the outer ends of said slideable plates for engagement with the facing sides of said concrete abutments, means for rigidly holding said slideable plates in adjusted position 35 for regulating the length of the ties, horizontal plates detachably carried by said vertical plates, rail chairs detachably connected to the ends of said horizontal plates, means for wedging said rail chairs into firm binding engagement with the bases of T-rails, and said concrete abutments being provided with drainage ducts formed in and extending outwardly at an incline, communicating with the facing sides of said abutments at 40 the upper surface of the edges of said concrete bed.

In testimony whereof I affix my signature in presence of two witnesses.

IRA S. FISHER.
